BUST SUPPORTER

Jeanne Tachat, Paris, France, assignor to
Société Anonyme Bernard & Cie, Paris FranceApplication July 7, 1937, Serial No. 152,321
In France September 18, 1936

3 Claims. (Cl. 2—42)

The present invention relates to a bust supporter of a simplicity unknown up to this day owing to the fact that it does not comprise any supporting member taking a bearing on the shoulders or on the waist; it is in fact simply composed of two breast-pockets, the inner edges of which are connected by a very short bond and the outer edges of which are connected by a bond passing round the bust.

The invention is based on the unexpected constatation that it suffices to provide the periphery of the breast-pockets with a flexible band having suitable properties of adherence to the skin for holding these breast-pockets stationary on the bust in the position where they have been placed, whatever may be the movements of the body. This adherence can be ensured for instance as in certain known fabrics by small rubber or like projections, particularly by gum threads incorporated in the fabric and forming on one of its faces very small projecting loops. It suffices moreover that the breast-pockets should be provided with such immobilization means on portions only of their periphery or of their surface, for instance at regular intervals.

Owing to this expedient, it is thus possible to make a new type of bust supporter which fits on the bust only at the places where it is useful, rendering the chest firmer and holding it by the sole effect of the aesthetic shape given to the pockets, so that, on the one hand, it is suited to all fashionable low-necked dresses and that, on the other hand, it seems impossible to exceed its simplicity and its efficiency.

The accompanying drawing illustrates, by way of example, an embodiment of a bust supporter according to this invention, seen from the interior and developed.

Fig. 1 is a front view.

Fig. 2 shows a detail.

1 designates the breast-pockets provided with a more or less rigid stiffening ring 1a which extends on a portion of their periphery, and is interrupted on the outer side on the remaining portion of this periphery so as not to hinder the movements of the bust and of the arms, 2 designates a bond connecting their inner edges, 3 a dorsal bond connecting their outer edges, and 4 a flexible band, of such a nature as to adhere to the skin, that is to say to oppose a very great resistance to any slipping movement against the latter. In the example illustrated, this band is entirely visible on the left-hand breast-pocket, whilst on the right-hand breast-pocket its adherence projections have been indicated only on

a portion of the periphery in order to more clearly show the stiffening element 1a enclosed in the edges of the breast-pocket. This band 4 being sewn on the periphery of each breast-pocket, fits on the bust around each breast when the bust supporter is placed in position and that the bond 3 is attached. In these conditions, it is unnecessary that this bond 3 should be tightly stretched, as the least pressure is sufficient for producing and maintaining an adherence sufficient for preventing any displacement of the edge of the breast-pockets as well upwardly as downwardly or laterally. On the contrary, it is only necessary to stretch the bond 3 as slightly as possible so as not to create any unnecessary compression. It is to be noted that the contact of the adhering band 4 with the bust does not create any uncomfortable and does not injure the skin, even when this contact is prolonged and whatever may be the movements of the body.

Owing to the absence of firmly stretched bonds and of any rigid or relatively rigid supporting members, the supporting and correcting action of the bust supporter no longer depends on the conformation of the pockets 1 themselves and can, consequently, be easily determined and adjusted when making said pockets.

In the embodiment illustrated, the bond 3 is composed of an elastic ribbon 3a provided with a series of button holes and with two triangular tabs 3b sewn to the outer edges of the breast-pockets, one of the ends of the ribbon 3a being permanently attached to one of the tabs 3b and being secured to the other tab by a button 3c. These details can however be modified without departing from the scope of the invention; for instance, one of the edges of each tab 3b, or even its two edges can be themselves of an elastic nature. The nature of the fabric of the breast-pockets can also vary, as well as that of the band 4 or of the other similar adherence means which will be arranged on the entire periphery or on a portion of the periphery of these breast-pockets.

Although it appears preferable to arrange these adherence means mainly on the edges of the breast-pockets, it will also be possible, without departing from the scope of the invention, to also arrange them at other portions of said breast-pockets, for instance on the upper part of the tabs 3b, or also on their lower part, etc., so that their adherence should be exerted on the breasts themselves or near the latter.

Fig. 2 illustrates in top plan view the stiffening element 1a of the left-hand breast-pocket, and

shows that its upper part is cambered at the top and forwardly at 1b in order to conform to the shape of the bust above the breast and not to create any uncomfortableness forwardly of the armpit. This convenient conformation, of course symmetrical for the right-hand breast-pocket, is applicable to all kinds of bust supporters whatever may be their mode of attachment.

I claim:

- 10 1. In a garment, the combination of two breast pockets connected together by a front bond and maintained upon the body by dorsal bands starting from the external edge of each pocket and attached at the back at the level of the breast,
- 15 2. A border extending around each breast-pocket,

said border being so shaped as to enclose the breast, a reinforcing element which is interrupted only on the external side, and a non-slipping lining covering the said border on the side bearing upon the skin.

2. A garment as claimed in claim 1, in which said non-slipping lining is constituted by gum threads embedded in the fabric of said border and forming small projecting loops upon that side of the border coming in contact with the skin.

3. A garment as claimed in claim 1, in which said non-slipping lining is provided on the internal side of the dorsal bands forming a belt.
